UNITED STATES PATENT OFFICE.

HARRY F. SMITH, OF LEXINGTON, OHIO, ASSIGNOR, BY MESNE ASSIGNMENTS, TO THE GAS RESEARCH COMPANY, OF DAYTON, OHIO, A CORPORATION OF OHIO.

STEAM REGULATION.

1,397,554.

Specification of Letters Patent.

Patented Nov. 22, 1921.

Application filed August 25, 1917. Serial No. 188,234.

To all whom it may concern:

Be it known that I, HARRY F. SMITH, a citizen of the United States of America, residing at Lexington, Richland county, Ohio, have invented certain new and useful Improvements in Steam Regulation, of which the following is a full, clear, and exact description.

This invention relates to a method of regulating the supply of steam to the generating chamber of a gas producer by means of the hydrogen content of the gas produced, and to a form of apparatus for carrying that method into effect.

It is the general practice, in generating producer gas, to pass a mixture of air and moisture through a bed of incandescent carbonaceous material. The gas thus produced consists principally of a mixture of hydrogen, liberated upon the decomposition of the moisture passed through the incandescent carbonaceous material, carbon monoxid, formed by combination of some of the carbon with the oxygen of the air and the oxygen liberated from the decomposed moisture, and inert gases. It is evident that the quality of the gas is dependent upon the relative proportion of air and moisture introduced into the generating chamber; for the amount of hydrogen present is proportional to the amount of moisture thus introduced. In order to secure a gas having a predetermined quality it is, therefore, necessary to regulate the proportions of air and moisture introduced. This moisture is usually in the form of steam, which may be introduced directly into the generating chamber, or into a saturator, where the air to be introduced into the generating chamber takes up a definite quantity of moisture, which quantity is dependent upon the temperature, the temperature in turn being of course dependent upon the amount of steam present. This steam may be taken from a special source of supply, or from the exhaust of the engine driving the pump, which serves, in the case of a pressure producer, to force the mixture of air and moisture through the generating chamber, or in the case of a suction producer, to draw the air and moisture through the generating chamber. The desired quality of gas may therefore be secured by regulating the amount of steam fed to the producer.

This regulation of the steam may be brought about in several different ways, each of which is more or less effective. I prefer to regulate the supply of moisture to the generating chamber according to the quality of the gas itself. In such regulation, I govern the supply of moisture by the hydrogen content of the gas, and in carrying out such regulation my apparatus is so arranged that an increasing quantity of hydrogen over that normally contained in the gas will bring about a closing movement of the valve governing the steam pipe leading to the generating chamber, while a decreasing amount of hydrogen will bring about an opening movement of the valve controlling the supply of steam to the generating chamber.

The principal object of my invention therefore, is to provide an effective method for regulating the supply of steam or moisture to the generating chamber according to the hydrogen content of the gas, and to provide an apparatus which is sufficiently sensitive, sufficiently accurate and still sufficiently substantial to permit of its practical application for carrying such method into effect.

My method of regulation is based on the fact that as the hydrogen content of the gas increases the specific gravity of that gas will tend to decrease, and, conversely, that as the hydrogen content of the gas decreases the specific gravity will tend to increase. And on the further fact that the quantity of hydrogen present in producer gas is dependent upon the amount of moisture introduced into the generating chamber. These facts being recognized, variations in the specific gravity of the gas flowing from the producer are used to bring about corresponding variations in the opening of the valve controlling the supply of steam to the generating chamber in order to thus secure a definite hydrogen content of the gas. In carrying this method of regulation into effect I make use of the apparatus illustrated in the drawing herewith, parts of this apparatus being shown in elevation and other parts in section in order to more clearly disclose the structure and mode of operation thereof.

In the apparatus disclosed, 1 is a gas main for conveying the gas produced in the generating chamber to any desired place of use

or storage. Leading from this main is a pipe 2, which opens into the lower end of a vessel 3. This vessel 3 contains a solution of caustic potash for removing all carbon dioxid from the gas passing therethrough. The only constituent part of the gas thus removed is the carbon dioxid. The specific gravities of the other constituents, with the exception of hydrogen, are about the same, 10 so that variations in the relative amounts thereof will not substantially affect the specific gravity of the gas as a whole. Variations in the amounts of either hydrogen or carbon dioxid, however, will affect the specific gravity of the gas as a whole and it is thus necessary to remove the latter if any specially accurate regulation is to be attempted based on varying amounts of hydrogen. From the upper end of the vessel 3 a 20 pipe 4 leads to the valve 5.

The valve 5 has four ports through its casing, arranged at intervals of 90 degrees. One of these ports, as stated above, is connected to the pipe 4. Another port, that 25 one located 180 degrees from the port connected with the pipe 4, is connected with a pipe 6, which communicates with the corresponding mechanism from the steam valve regulator. The other two ports, which are 30 located midway between the two above mentioned ports and at opposite sides of the valve, are connected with two stand-pipes 7 and 8. The valve plug 9 has therein two passages 10 so arranged that the pipes 4, 6, 35 7 and 8 can be brought into register in pairs. Attached to the valve plug 9 is an actuating mechanism, (not shown,) adapted to impart thereto a continuous rotary motion so that each of the stand-pipes 7 and 8 is brought 40 alternately into register with the pipe 4 and the pipe 6. As shown, stand-pipe 8 is connected to the pipe 6, while stand-pipe 7 is connected to the pipe 4. Rotation of the valve 5 will connect stand-pipe 7 with the 45 pipe 6 and stand-pipe 8 with the pipe 4. In this way, one of the stand-pipes is receiving a new charge of hydrogen containing gas from the supply pipe 4, while the other stand-pipe is connected through the pipe 6 50 with the regulator actuating mechanism to bring about in that mechanism a change corresponding to the specific gravity of that particular charge of gas. It is evident that by rotating the valve, the stand-pipes will 55 be each alternately connected to the supply pipe 4 and to the pipe 6 to thus introduce into the stand-pipes new charges of gas, which will, because of variations in specific gravity, cause the regulator mechanism to 60 vary with the opening of the valve governing the steam supply.

The pipe 6 leads into the lower part of a gasometer 11, the upper part of which is connected to one end of the lever 12. The 65 lever 12 is fulcrumed at 13 and has attached

thereto, between the fulcrum and the point of connection with the upper bell of the gasometer, a link 14.

Located in the pipe 15, which supplies the steam to the generating chamber or 70 saturator, is a valve 16 adapted to control the flow of steam therethrough. This valve 16 has its stem operatively connected to the diaphragm 17 of the diaphragm regulator 18. In the regulator 18 is a spring 19 so 75 arranged as to normally tend to close the valve 16. Coöperating with the spring 19 is a threaded cap 20, whereby the tension of the spring may be regulated to meet any variations in operating conditions. Connected to the regulator is a pipe 21 leading from any source of supply of fluid under pressure. I prefer to use compressed air as the fluid under pressure, but of course any other pressure fluid desired can be used 80 in place thereof. Situated in the pipe 21 is a valve 22 adapted to control the flow of pressure fluid to the regulator 18. Leading off from the pipe 21, between the valve 22 and the regulator 18, is a branch pipe 23 85 controlled by a valve 24. The valve 24, under normal conditions, is somewhat open to permit leakage of the pressure fluid in the pipe 21 therethrough; the amount of pressure fluid admitted through the valve 22, 90 the leakage through the valve 24 and the tension of the spring 19 being so adjusted that under normal conditions a predetermined opening of the valve 16 will be maintained. Adjustably connected to the stem 100 of the valve 24 is a link 25, pivotally connected to the lever 12. Attached to the pipe 21 adjacent the regulator 18 is a pressure gage 26.

Any up or down motion of the upper bell 105 of the gasometer 11 will produce a corresponding motion of the lever 12 to move the valve 24 toward or from its seat. Such movement of the valve 24, in changing the amount of opening thereat, will change the 110 pressure in the regulator 18 and thus vary the amount of opening of the steam controlled valve 16. If, therefore, there is a variation in the specific gravity of the charge of gas in either of the stand-pipes 115 7-8, such variation will be transmitted to the gasometer and through it and the mechanism coöperating therewith to the steam valve 16. Since all the carbon dioxid, which will tend to effect the specific gravity 120 of the gas is removed in the vessel 3, it is obvious that any changes in specific gravity of such gas will be due to a varying hydrogen content. If the specific gravity increases, it is due to a decrease of hydrogen, 125 which means an insufficient supply of steam. This increase of specific gravity, which is merely another way of saying that the weight of the column of gas in the stand-pipe has increased, will be transmitted to 130

the gasometer 11 and tend to raise the upper bell thereof. Such upward movement imparts a closing movement to the valve 24 and results in the building up of pressure in 5 the regulator 18, with a consequent opening of the valve 16 to supply more steam to the generating chamber. If this opening of the valve 16 results in the supply of too much steam to the generating chamber, there will 10 be of course too great an increase in the quantity of hydrogen present, with a corresponding decrease in the specific gravity, which decrease in specific gravity will tend to return the steam control valve 16 to normal position. And obviously, any decrease 15 in the specific gravity would, in like manner, cause a further closing of the valve 16, with a consequent decrease in the amount of steam supplied to the generating chamber to 20 bring about a corresponding decrease in the amount of hydrogen present in the gas.

The stand-pipes 7 and 8 are of considerable length in order to hold a large quantity of gas to thus increase the actual weight 25 changes due to specific gravity variations. Also the valve 5 has the passages therein so arranged that the flow of gas from the pipe 4 to each of the stand-pipes is cut off sufficiently in advance of the time of connecting either of these stand-pipes to the 30 pipe 6 to permit of the gas therein coming to a complete rest before being so connected. In this way, all errors due to flow of the gas in the stand-pipes are entirely eliminated, 35 since the gas will have come to a complete rest before it is connected with the gasometer 11.

It is of course evident that more than two stand-pipes may be used if desired, the number 40 being dependent upon the number and arrangement of passages in the valve 5. A greater number of stand-pipes is advantageous at times, since a more continuous regulation of the steam can be secured; for, 45 by using a greater number of stand-pipes, the valve 5 can be so arranged that one of the stand-pipes is always in connection with the gasometer 11 so that a truly continuous regulation of the valve 16 can be secured.

50 For very accurate control the carbon-dioxide contained in the gas should be removed by utilizing the tank 3 and its contained caustic solution. In general practice, however, especially in the generation of 55 producer gas, there is, during operation, comparatively slight variation in the proportion of carbon-dioxide present in the gas. But there may be, and frequently is, very substantial variation in the proportion of 60 hydrogen present. Further the proportion of carbon-dioxide present in the gas is usually considerably lower than the proportion of hydrogen present. Unless especially accurate control is desired, therefore, the removal of the carbon-dioxide may be dis-

pensed with, and a satisfactory control secured by varying the amount of moisture supplied, in accordance with the specific gravity of the gas generated, without the removal of any of its constituents. 70

My method of steam regulation is by no means limited in its operation to the precise form of apparatus disclosed, for it is quite evident that many variations in the form of that apparatus can be made. And other 75 forms of apparatus entirely unlike that disclosed might easily be devised for carrying this method into effect. For instance, other types of valves might readily be substituted for the rotating valve disclosed. Also other 80 types of apparatus might be substituted for the gasometer 11, and, too, for the regulator 18.

While the method herein described, and the form of apparatus for carrying this 85 method into effect, constitute preferred embodiments of the invention, it is to be understood that the invention is not limited to this precise method and form of apparatus, and that changes may be made in either 90 without departing from the scope of the invention which is defined in the appended claims.

What I claim as new and desire to secure by Letters Patent is—

1. The method, in the generation of gas in which air and moisture are supplied to the gas generating chamber, which consists in continuously controlling the amount of moisture supplied according to the specific gravity 95 of the gas produced.

2. The method, in the generation of gas in which air and moisture are supplied to the gas generating chamber, which consists in automatically varying the amount of moisture supplied according to the hydrogen content of the gas produced.

3. The method, in the generation of gas in which air and moisture are supplied to the gas generating chamber, which consists in 110 removing all carbon-dioxide from portions of the gas and controlling the moisture supply according to variations in the specific gravity of such portions.

4. The method, in the generation of gas in which air and moisture are supplied to the gas generating chamber, which consists in removing all carbon-dioxide from portions of the gas and controlling the moisture supply according to the hydrogen content of such 115 portions.

5. The method, in the generation of gas in which air and moisture are supplied to the gas generating chamber, which consists in automatically collecting portions of the 120 gas and controlling the amount of moisture supplied according to the specific gravity of such portions.

6. The method, in the generation of gas in which air and moisture are supplied to the 125

gas generating chamber, which consists in collecting portions of the gas produced, allowing these portions to come to rest, and then varying the supply of moisture according to variations in specific gravity of the said portions of gas.

7. The method, in the generation of gas in which air and moisture are supplied to the gas generating chamber, which consists in varying the supply of moisture at intervals according to the specific gravity of the gas produced.

8. In a moisture regulator, a moisture supply pipe, a valve for controlling flow therethrough, mechanism for governing said valve, and separate actuating means for said governing mechanism comprising a specific gravity stand-pipe.

9. In a moisture regulator for gas producers, a moisture supply pipe, a valve for controlling flow therethrough, operating mechanism for said valve, and actuating means for said operating mechanism, said actuating means being responsive to variations in specific gravity of the gas produced.

10. In a moisture regulator for gas producers, a moisture supply pipe leading to the producer, a valve for controlling flow therethrough, operating mechanism for said valve, and actuating means for said operating mechanism, said actuating means being responsive to variations in the hydrogen content of the gas produced.

11. In a moisture regulator, a moisture supply pipe, a valve for controlling flow therethrough, pressure actuated means for operating said valve, and means for actuating said pressure operated means comprising specific gravity stand-pipes.

12. The method of regulating the amount of a certain fluid material supplied to a device containing other material adapted to cause a reaction with said certain fluid material to produce a resulting material, which consists in automatically varying the amount of said fluid material supplied according to variations in the composition of said resulting material.

13. The method of regulating the amount of a certain fluid material supplied to a device containing other material adapted to cause a reaction with said certain fluid material to produce a resultant material, which consists in automatically varying the amount of said fluid material supplied according to variations in the specific gravity of the said resultant material.

14. The method of regulating the amount of a certain fluid material supplied to a device containing other material adapted to cause a reaction with said certain fluid material to produce a desired resulting material, which consists in collecting portions of said resulting material, and automatically varying the amount of said certain fluid material

supplied according to variations in the specific gravity of said collected portions.

15. A method of regulating the amount of a certain fluid material supplied to a device containing other material adapted to cause a reaction with said certain fluid material to produce a desired resulting material, which consists in collecting portions of said resulting material, allowing such collected portions to come to rest, and automatically varying the amount of said certain fluid material supplied according to variations in the specific gravity of said collected portions.

16. The method, in the generation of gas in which air and moisture are supplied to the gas generating chamber, which consists in collecting portions of the gas generated; removing carbon dioxid therefrom; allowing carbon dioxid free portions to come to rest; and then varying the supply of moisture according to variations in the specific gravity of such portions.

17. In a device for controlling the supply of moisture to a gas generator, a moisture supply pipe leading to said generator; a valve for controlling flow through said pipe, operating mechanism for said valve; means for withdrawing portions of the gas produced and removing carbon dioxid therefrom; and means for actuating the valve operating mechanism to accord with variations in the specific gravity of the carbon dioxid free gas.

18. In a device for controlling the supply of moisture to a gas generator, a moisture supply pipe leading to said generator; a valve for controlling flow through said pipe, operating mechanism for said valve; means for withdrawing portions of the gas produced and removing carbon dioxid therefrom; means for allowing such portions of gas to come to rest; and means for actuating the valve operating mechanism to accord with variations in the specific gravity of the collected portions of carbon dioxid free gas.

19. The method of regulating the amount of a certain fluid supplied to a device for mixing a plurality of fluids which consists in varying the amount of said certain fluid supplied according to the specific gravity of the resultant fluid mixture.

20. The method of operating a gas generator which comprises the introducing of moisture into said generator, and controlling the quantity of moisture supplied to maintain substantially constant the specific gravity of the generated gas.

21. A device for controlling the supply of moisture to a gas generator, comprising a moisture supply pipe, through which moisture is introduced into the generator, a controlling valve therein; pressure responsive operating mechanism for said controlling

130

- valve, a pipe for supplying pressure fluid to said operating mechanism, a valve in said last named pipe for regulating the supply of pressure fluid to said operating mechanism; and operating means for said last named valve responsive to variations in specific gravity of the generated gas.
22. A device for controlling the supply of moisture to a gas generator, comprising a moisture supply pipe, through which moisture is introduced into the generator, a controlling valve therein; pressure responsive operating mechanism for said controlling valve, a pipe for supplying pressure fluid to said operating mechanism, a valve in said last named pipe for regulating the supply of pressure fluid to said operating mechanism; pressure responsive means operatively connected to said last named valve,
- 20 a specific gravity standpipe connected to said means, and means for trapping in said standpipe some of the generated gas, the construction being such that the said pressure responsive means will operate the said last named means in accordance with the specific gravity of the gas trapped in said standpipe.
23. A device for controlling the supply of moisture to a gas generator having a delivery main, comprising a moisture supply pipe, through which moisture is introduced into the generator, a controlling valve therein; pressure responsive operating mechanism for said valve, a pipe for supplying pressure fluid to said operating mechanism,
- 5 a bleed valve in said pipe; a gasometer, the upper bell of which is operatively connected to said bleed valve; a specific gravity standpipe connected to said gasometer; and means for connecting said standpipe to the interior 40 of the gasometer or to the delivery main.
24. The method, in the generation of gas in which air and moisture are supplied to the generating chamber of a gas producer, means being provided for controlling the 45 quantity of moisture supplied, which consists in withdrawing a portion of the generated gas, and collecting fractions of such withdrawn gas in apparatus constructed to actuate the moisture controlling means to 50 regulate the amount of moisture introduced into the generating chamber of the producer to accord with the specific gravity of the generated gas.
25. The method, in the generation of gas 55 in which air and moisture are supplied to the generating chamber of a gas producer, means being provided for controlling the quantity of moisture supplied, which consists in withdrawing a portion of the generated gas, removing carbon-dioxide therefrom, and collecting fractions of such carbon-dioxide free gas in specific gravity apparatus, constructed to actuate the moisture controlling means, to regulate the amount 60 of moisture introduced into the generating chamber of the producer to accord with the specific gravity of the generated gas.

In testimony whereof I affix my signature.
HARRY F. SMITH.
